UNITED STATES PATENT OFFICE.

EDWARD BIGNELL, OF LINCOLN, NEBRASKA.

CONCRETE PILING.

1,026,144.

Specification of Letters Patent.

Patented May 14, 1912.

Application filed February 19, 1912. Serial No. 678,470.

To all whom it may concern:

Be it known that I, EDWARD BIGNELL, a citizen of the United States, residing at Lincoln, in the county of Lancaster and State of Nebraska, have invented certain new and useful Improvements in Concrete Piling, of which the following is a specification.

This invention has reference to an improvement in piling, of the class wherein the pile is formed of a cement or concrete body within which is contained and upon which is mounted structural parts for conducting air or water, under pressure, to be discharged at its bottom and sides, while in an upright position, to excavate the ground, so that it may sink by gravity to a required depth.

The invention is presented as an improvement of the concrete piling illustrated and claimed in a companion application for Letters Patent filed by Edward Bignell July 31, 1911, Serial No. 641,608. While the herein described construction is similar thereto, it embodies improved features which will be fully explained and claimed, said improvements consisting, in part, of bearings at the lower terminal of the pile, and discharge-members or nozzles projecting below the bottom of the pile and so arranged that they may be conveniently withdrawn from the bearings after the pile has been sunk; also a more extensive and effective discharge for excavating the ground, and certain other useful features.

By use of the herein described construction, all of the metallic operating parts may be removed from the pile after it has been sunk, whereby the expenses in the practice of sinking concrete piles may be materially reduced.

The invention illustrates the employment of a plurality of barrels, housing-tubes or reservoirs of uniform length with closed lower ends, said tubes or reservoirs being formed in and extending longitudinally of and opening upon the upper end of the pile for conducting water, under pressure, each being provided with numerous conduits transversely traversing the concrete body of the pile; and the employment of pipes disposed in the reservoirs for conducting water, under pressure, and provided with discharge-members or nozzles which extend below the flat bottom of the pile; also the invention illustrates the employment of me-

tallic screw-caps which may be secured for use, after the couplings have been removed, as bearing-blocks upon the upper ends of the piles, this being useful for bridge-work; and reinforcing means employed in forming the concrete tongue and groove, at opposite sides of the pile, for connecting one pile with another.

The invention consists of the novel construction, combination and arrangement of parts as described herein and claimed, and as illustrated in the drawing, wherein,—

Figure 1 is a side elevation of a concrete pile embodying my invention, parts being broken away and in section to more clearly show construction. Fig. 2 is a side elevation of the pile on a smaller scale than Fig. 1, the nozzles being removed from the bottom of the pile, certain operating parts being removed from the upper end of the pile and replaced by the screw-cap. Fig. 3 is a transverse section of the pile on line *a a* of Fig. 1. Fig. 4 is an enlarged detail relating to Fig. 1 to clearly show the mountings of the nozzles in the base or bearing-plate of the pile, the tubular housing or reservoir and the bearing-plate being in section, the boss of the nozzle being broken away. Fig. 5 is a side view, partly in section, of the screw-cap. Fig. 6 is a bottom plan view of a pile, a part of a connected pile also being shown. Fig. 7 is a view, partly broken, showing the lower end of a pile provided with a single reservoir or housing-tube, a single conducting pipe and single nozzle.

Referring now to the drawing for a more particular description, numeral 8 indicates the elongated body of a pile constructed of concrete, and preferably having upon its base a metallic bearing-plate 9, said plate being disposed at right angles to the longitudinal axis of the pile and suitably secured thereto. By this construction a flat bottom is provided for the pile, this tending to prevent breakage, and also providing greater stability for the pile when used in soft ground or riparian work. Upon the sides of the pile, opposite to each other, are respectively formed the longitudinal tongue or ridge 10 and the longitudinal groove 11, these parts preferably being reinforced by metallic strands 12 which may be embedded in the concrete material at the time the pile is molded or formed.

At 13 are indicated housing-tubes dis-

posed within and extending longitudinally of the body of the pile, their upper ends opening upon the upper flat terminal of the pile, and their lower ends being seated upon the bearing-plate. Depressions or annular recesses 14 may be formed in the upper end of the pile to circumscribe members 13, and the upper ends of said members 13 are threaded as indicated at *b*.

10 At 15 are indicated discharge-members or nozzles, each disposed in a manner to project below the base of the pile, and having a threaded connection *c* with plate 9, and provided with a boss 16 for a seating upon the inner face of plate 9; the bosses are internally threaded as indicated at *d* to connect with the threaded lower terminal of the conducting pipes 17. A conducting-pipe is provided for and is disposed within 15 each tube 13 and, preferably, they extend above the body of the pile.

At 18 are indicated T pipe-couplings which may be threaded upon the upper ends of members 13, by entering recesses 14, each 20 of these couplings being provided with a supply-pipe 19; the couplings provide a conduit for water within the housing-tubes 13 from said supply pipes, an arrangement of threaded bushings *e* being provided for 25 the mounting of the upper end of each conducting pipe 17 and preventing the escape of water from the upper ends of said tubes 13.

At 20 are indicated supply pipes mounted upon the upper ends of conducting pipes 30 17; and water under pressure from any suitable source may be conducted to said pipe 17 and may be conducted below the bottom of the pile and discharged through the nozzles. In the concrete body of the pile 35 and particularly toward its lower end, are formed apertures 21. They are inclined upwardly and outwardly from each housing-tube 13 and form passageways from said tubes to open promiscuously upon all of the 40 sides of the pile, the function being that the water thus discharged from pipes 13 will loosen the ground at the sides of the pile to remove adhesions and reduce friction, so that the pile may sink more readily.

45 It will be understood that housing tubes 13, bearing-plate 9 and the reinforcing strands 12 are secured in rigid relation with the pile at the time the latter is molded. All of the other metallic parts employed are 50 of considerable value, comparatively, and the construction is such that they may be removed after the pile has been sunk.

55 After a pile has been constructed, the nozzles may be threaded in the bearing-plate; the conducting pipe 17 may be threaded in the bosses of the nozzles, and the pipe couplings may be mounted upon the upper ends of the housing tubes, and the pile may then be sunk.

60 65 When the pile has been disposed verti-

cally to be sunk, water under pressure is caused to pass through pipes 17. Since the nozzles project to a considerable distance below the bottom of the pile, the ground will be loosened and the pile will sink on account 70 of its weight. After the pile has been partly sunk, the operator may cause water under pressure to pass within all or any single one of supply pipes 19, and since the water will pass within tubes 13 and thence outwardly 75 through apertures 21, any adhesion or friction caused by the ground upon the sides of the pile will be reduced, and the operation of sinking the pile will be facilitated.

By referring to Fig. 4 it will be seen that the nozzles and conducting pipes are reversely threaded; and therefore a pipe 17 may be rotated in one direction to cause an upward movement of the nozzle, said nozzle leaving the threaded mounting in the bearing-plate and passing within the housing-tube 13, and by these means the conducting pipes and nozzles may be removed, after the pile had been sunk. Also it will be noted, by reference to Fig. 4 that a conducting-pipe 17 may be rotated in a direction to cause its release from the nozzle, said nozzle remaining in its bearings, and this construction is of advantage since in some instances, it may be desirable to remove the piles from the ground for replacement; and for the removal of a pile it is desirable and quite necessary to loosen the ground by action of the injected water in the same manner already described, so that, by use of 80 derricks or other lifting means they may be removed. And the present construction of a pile and operating parts therefor has for one of its important features the provision of means for aiding in the removal as well 85 as for sinking the pile.

After a pile has been sunk, another pile 90 may be connected therewith, the tongue or ridge 10 of one pile engaging in the groove 11 of an adjacent pile, and this is useful 95 when forming piers or bridge-work.

100 A screw-cap or coupling is indicated at 22. It is provided at its middle with an interiorly-threaded, annular projection 23 for a mounting upon the threaded terminal *b* of one of members 13, or the one located substantially at the longitudinal middle of the pile. After the cap has been rotated, its projection 23 will be disposed within a 105 recess 14, and the screw-cap provides a bearing-head for the complete pile.

Fig. 7 shows a pile having a body portion 8' of concrete with a longitudinal ridge 10', and a longitudinal groove 11' formed upon two of its sides, opposite to each other; a 110 single, central longitudinal housing-tube 13' being employed, with transverse branches, jet-apertures or passageways 21' communicating therewith and providing discharge ports at the sides of the pile. It also shows 115 120 125 130

5 a conducting pipe 17' disposed in the housing-tube and provided with a nozzle 15' projecting below the flat bottom of the pile. The construction and operation is substantially the same as already described. It is useful where the ground is wet or marshy or otherwise in condition to offer a slight resistance to the sinking of the pile. Also this modified form may be used in the construction of piles having a limited thickness or length.

10 In constructing the herein described piles, the longitudinal tongues and grooves may be used or omitted as may be desired, and 15 while I have shown a pile substantially square, in cross-section, I do not limit myself to this feature.

15 Among some of the advantages to be derived by use of the herein described pile, it 20 may be stated that the ground is rendered loose and plastic at a considerable distance below the bottom of the pile, and therefore piles with flat bottoms may be sunk more readily than by other means. Also since, as 25 shown in Fig. 1, a provision is made for a plurality of jet-discharges below the flat bottom, a control may be made in the downward movement of the pile to maintain the same vertically, the control of each of the 30 discharges through pipes 17 being separate and distinct from the other. This is particularly useful where the piles are sunk in the bottoms of flowing streams or in yielding ground, for, as is obvious, if the excavation be made at one side and below the bottom of the pile, there will be a tendency for a movement of the lower end of the pile 35 in a direction of the excavation.

40 While cement or concrete piles have great comparative durability, they are practically useless unless operative mechanism is provided for sinking them. These operative parts are expensive, comparatively. In the present instance the construction has been 45 greatly simplified, also the parts are few and may be conveniently made; and practically all of the metallic parts are removable from the pile after it has been sunk, except the housing tubes which operate to reinforce 50 the pile.

Having fully described my invention, what I claim is,—

55 1. In combination with the elongated body of a pile having a flat bottom, a plurality of nozzles mounted upon and projecting below said bottom, and means to conduct separate columns of water under pressure through the pile, each of said columns communicating with one of said nozzles.

60 2. In combination with the elongated body of a pile having a flat bottom, a nozzle mounted upon and projecting below said bottom, a duct formed within and extending longitudinally of the pile adapted to 65 conduct water under pressure to said nozzle.

3. The combination of a pile formed with longitudinal apertures and transverse passageways communicating with the apertures, to open upon its sides; a bearing-plate provided with nozzles and mounted upon the 70 bottom of the pile to form a closure for said apertures; conducting pipes communicating with the nozzles and traversing said apertures, said nozzles projecting below the bearing-plate. 75

4. In combination with a pile having a body of adhesive material, a housing-tube embedded within and traversing the pile longitudinally, said tube being provided with a closure at its lower terminal and having 80 branches between its terminals opening upon the sides of the pile; a conducting pipe traversing the housing-tube, and a nozzle in communication with the conducting-pipe and projecting below the bottom of said pile. 85

5. In combination with a pile having a body of adhesive material, a bearing-plate disposed at substantially right angles to the longitudinal axis and mounted upon the bottom of the pile; a nozzle mounted in and 90 projecting below the bearing-plate; and a pipe adapted to conduct water under pressure longitudinally traversing the pile and having removable connection with said nozzle. 95

6. In combination with a pile having a longitudinally apertured body and transverse passageways communicating with the aperture and opening upon its sides; a flat bearing-plate mounted upon the bottom and disposed substantially at right angles to the longitudinal axis of the pile; a nozzle removably mounted in and projecting below the bearing-plate, and a conducting pipe traversing the aperture and removably 100 mounted upon said nozzle.

7. In combination with a pile having a plurality of apertures formed longitudinally therein and transverse passageways communicating with said apertures and opening upon its sides; a substantially flat bearing-plate mounted upon the bottom and disposed substantially at right angles to the longitudinal axis of the pile; nozzles removably mounted in and projecting below the 110 bearing-plate; and a plurality of conducting-pipes, each being mounted at its upper end upon the upper terminal of the pile and traversing one of said apertures and having removable connection with a nozzle. 115

8. In combination with the elongated body of a pile formed with apertures extending longitudinally therethrough, with transverse branches opening upon its sides, and formed with an oppositely-disposed tongue and groove extending longitudinally upon its sides; a tubular member mounted in each aperture in communication with the branches thereof; a substantially flat bearing-plate mounted upon the bottom of the pile and 125 130

forming closures for said apertures and tubular members, said plate being disposed substantially at right angles to the longitudinal axis of the pile; nozzles threaded in 5 and projecting below the bearing-plate; conducting-pipes disposed in said tubular members and having threaded connections with said nozzles; each of said tubular members being provided with a separate supply pipe 10 for conducting water under pressure thereto for a discharge thereof through its transverse branches; each of the conducting pipes being provided with a separate pipe to supply water under pressure thereto for a discharge through one of said nozzles.

15 9. In combination with the elongated body of a pile provided with a longitudinally disposed tongue and groove, and with a sub-

stantially flat, transversely disposed bearing-plate upon its bottom; nozzles mounted in 20 and projecting below said bearing-plate; pipes traversing the body of the pile, said pipes being connected with and adapted to conduct a fluid or liquid element under pressure to said nozzles, said conducting pipes 25 being rotatable in one direction to cause their release from the nozzles, and being rotatable in an opposite direction to cause a release of the nozzles from said bearing-plate.

In testimony whereof I have affixed my signature in presence of two witnesses.

EDWARD BIGNELL.
